UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

TEMPORARY BINDER.

1,385,163.

Specification of Letters Patent. Patented July 19, 1921.

Application filed May 14, 1920. Serial No. 281,312.

To all whom it may concern:

Be it known that I, GEORGE P. WIGGINTON, a citizen of the United States, residing at the city and county of Kalamazoo, State of Michigan, have invented certain new and useful Improvements in Temporary Binders, of which the following is a specification.

This invention relates to improvements in temporary binders.

10 The main objects of this invention are:

First, to provide an improved temporary binder which is compact in structure and light in weight so that it may be easily carried about and at the same time one in which the sheets are bound in a neat and secure manner.

Second, to provide an improved temporary binder which is well adapted for holding loose sheets and circulars such as those of 20 loose leaf catalogues in which all of the sheets are securely bound when it is desired to handle them in the binder and at the same time they are readily freed as occasion may require.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing forming a 35 part of this specification, in which:

Figure I is a perspective view of a structure embodying the features of my invention.

Fig. II is a perspective view of the sheet body and posts removed as a unit from the 40 binder members.

Fig. III is a detail inside view of one of the covers showing the adjusting means for the binding strips of the embodiment illustrated in Figs. I to VI.

45 Fig. IV is a detail transverse section on a line corresponding to line 4—4 of Fig. V.

Fig. V is a detail longitudinal section on a line corresponding to line 5—5 of Fig. IV.

50 Fig. VI is a detail longitudinal section similar to Fig. V illustrating that the binder may be expanded to accommodate different thicknesses of sheet body.

Fig. VII is a plan view of one of the clamping members.

55 Fig. VIII is a detail section on a line cor-

responding to line 8—8 of Fig. IX showing an adaptation of my improvements to the post type of binder.

Fig. IX is a detail section on a line corresponding to line 9—9 of Fig. VIII.

60

In the drawing similar reference characters refer to similar parts throughout the several views, and the sectional views are taken looking in the direction of the little arrows at the ends of the section lines.

65

Referring to the drawing, the covers 1 of the structure illustrated in Figs. I to VII inclusive are provided with recesses or chambers 2 to receive the adjusting mechanism 3 and the ends of flexible back 4. The binding strips 5 are connected at one end to the adjusting mechanism 3 which is substantially that shown in Letters Patent No. 1,010,556 issued to me December 6, 1911. As the details of this adjusting mechanism form no 70 part of my present invention they are not further illustrated or described herein.

The binding strips 5 extend between the covers, being disposed through the clamping members 6 which are pivotally mounted on 75 the covers at 7, these clamping members being mounted substantially as shown in my said patent.

The sheets 8 are provided with notches 9 and with holes 10, the notches opening at the 80 binding edge of the sheets and the holes being disposed adjacent to the binding edges of the sheets. The notches 9 are in position to receive the binding strips 5 while the holes receive binding posts 11 having collar-like 85 heads 12 thereon adapted to engage the outer sheets of the sheet body as shown in Fig. IV and studs 13 on the outer sides of the heads adapted to engage the holes 14 in the clamping members.

90

With this arrangement of parts, when the clamping members are separated or retracted, the body of sheets bound by the post may be removed from the binder as a unit as shown in Fig. II, and the posts, being arranged from opposite sides of the sheet body, bind the sheets securely. The body of sheets is bound or clamped by the binder members when they are adjusted thereto with the posts engaging the holes or sockets in the 95 binder members.

95

The posts 11 are of the sectional post type so that they may be adapted to different quantities of sheets or different thicknesses of sheet body.

100

105

110

In the adaptation of my invention to a binder of the sectional post type, as shown in Figs. VIII and IX, the binding members or sectional posts 15 are mounted on the bottom binder member 16 and are adapted to project through the upper binder member 17 which is provided with a clutch means for adjustably securing the upper binder member to the posts. As such clutch means are well known in the art, I do not illustrate the same herein.

The posts 11 are provided with studs engaging holes in the binder members and are provided with heads the same as shown in the structure of Figs. I to VII.

My improvements are well adapted for light binders or where it is desirable to provide a comparatively light, simple binding means and at the same time one in which the sheets are securely held or bound and one which permits their rapid removal, as a unit or as individual sheets, or replacement as occasion requires.

I have illustrated and described my improvements in two forms or adaptations. I do not illustrate or describe other adaptations which I contemplate as I believe the disclosure made will enable those skilled in the art to which my invention relates to embody or adapt the same as the type of binders or the particular requirements render most desirable.

Having thus described my invention, what I claim as new and desire to secure by Letters Patent, is:

1. In a temporary binder, the combination with sheets provided with open notches in their binding edges and with holes adapted to receive posts, or covers, clamping members pivotally connected to said covers and having holes therein, binding strips extending between said covers and adapted to engage said notches of said sheets, said binding strips being arranged through said clamping members and provided with adjusting means, and posts engaging said holes in said sheets and provided with heads engaging the outer sheets and with studs engaging said holes in said clamping members whereby they are removably retained when the clamping members are adjusted to the sheet body, the posts being arranged from both sides of the sheet body and overlapping therein.

2. In a temporary binder, the combination with sheets provided with holes adapted to receive posts, of covers, clamping members pivotally connected to said covers and having holes therein, binding members extending between said clamping members, and posts engaging said holes in said sheets and provided with heads engaging the outer sheets and with studs engaging said holes in said clamping members whereby they are removably retained when the clamping

members are adjusted to the sheet body, the posts being arranged from both sides of the sheet body and overlapping therein.

3. In a temporary binder, the combination with sheets provided with open notches in their binding edges and with holes adapted to receive posts, of covers, clamping members pivotally connected to said covers and having holes therein, binding strips extending between said covers and adapted to engage said notches of said sheets, said binding strips being arranged through said clamping members and provided with adjusting means, and posts removably engaging said holes in said sheets and clamping members and provided with heads between the sheets and clamping members.

4. In a temporary binder, the combination with sheets provided with holes adapted to receive posts, of covers, clamping members pivotally connected to said covers and having holes therein, binding members extending between said clamping members, and posts removably engaging said holes in said sheets and clamping members and provided with heads between the sheets and clamping members.

5. In a temporary binder, the combination with sheets provided with open notches in their binding edges and with holes adapted to receive posts, of clamping members, binding members extending between said clamping members and adapted to engage said notches of said sheets, and posts provided with collar-like head portions disposed in the holes of said sheets from opposite sides of the sheet body and removably engaged with said clamping members, the posts being retained by the adjustment of the clamping members to the sheet body.

6. In a temporary binder, the combination with sheets provided with holes adapted to receive posts, of clamping members, binding members extending between said clamping members, and posts provided with collar-like head portions disposed in the holes of said sheets from opposite sides of the sheet body and removably engaged with said clamping members, the posts being retained by the adjustment of the clamping members to the sheet body.

7. In a temporary binder, the combination of binder members, binding members for said binder members and sheets having holes therein adapted to receive binding posts, and posts provided with heads disposed in the holes of the sheets from opposite sides of the sheet body to overlap therein and provided with studs detachably engaging said binder members.

8. In a temporary binder, the combination of binder members, sheets having holes therein adapted to receive binding posts, and posts provided with head members, said posts being disposed in the holes of the

- sheets and detachably engaging said binder members.
9. In a temporary binder, the combination of sheets provided with holes adapted to receive binding posts, of binder members, and posts engaging the holes of the sheets and detachably engaging said binder members and provided with head portions engaging the sheet body, the posts being arranged in 10 the sheet body from opposite sides and overlapping therein.
10. In a temporary binder, the combination of covers, clamping members pivotally connected to said covers, binding strips extending between said clamping members, and posts removably engaging said clamping members and provided with collar-like sheet engaging heads.
11. In a temporary binder, the combination of binder members, and posts detachably engaging said binder members and provided with head portions engaging the sheet body so that it may be removed with the posts from the binder members as a unit.
12. In a temporary binder, the combination of binder members, binding members for said binder members, and posts removably engaging said binder members and provided with sheet engaging heads.

In witness whereof I have hereunto set my 30 hand and seal in the presence of two witnesses.

GEORGE P. WIGGINGTON. [L.S.]
